(57) **CLAIM**

The ornamental design for a flask and cap, as shown and described.

DESCRIPTION

FIG. 1 is a top perspective view of a flask and cap showing our new design;

FIG. 2 is a right side elevation view thereof, the left side elevation view being a mirror image;

FIG. 3 is a front elevation view thereof;

FIG. 4 is a top plan view thereof;

FIG. 5 is a bottom plan view thereof;

FIG. 6 is an exploded top perspective view thereof;

FIG. 7 is a top perspective view of the collar portion of the claimed design;

FIG. 8 is a bottom perspective view thereof;

FIG. 9 is a top plan view thereof;

FIG. 10 is a bottom plan view thereof;

FIG. 11 is a front elevation view thereof, the rear elevation being identical;

FIG. 12 is a front elevation view of the flask portion of the claimed design;

FIG. 13 is a rear elevation view thereof;

FIG. 14 is a top plan view thereof;

FIG. 15 is a bottom plan view thereof;

FIG. 16 is a top perspective view of the cap portion of the claimed design;

FIG. 17 is a bottom perspective view thereof;

FIG. 18 is a top plan view thereof;

FIG. 19 is a bottom plan view thereof;

FIG. 20 is a front elevation view thereof; and,

FIG. 21 is a right side elevation view thereof, the left side elevation view being a mirror image.

The broken lines in the drawings showing the inner details of the collar and cap portions the threaded pour spout and neck of the and the bottom surfaces illustrate the portions of the design that form no part of the claim.
